SHOWER CURTAIN HOOK OR SIMILAR ARTICLE

Heinz Nathanson, 160 5th Ave.,
New York, N.Y. 10010

Filed Jan. 18, 1966, Ser. No. 660

Term of patent 7 years

(Cl. D21—1)

FIG. 1

FIG. 2

FIG. 1 is a front perspective view of a shower curtain hook or similar article showing my new design.

FIG. 2 is a side elevational view.

The back of the design is substantially plain.

I claim:

The ornamental design for a shower curtain hook or similar article, substantially as shown and described.
